UNITED STATES PATENT OFFICE.

GEORGE H. DUKE, OF HOTCHKISS, COLORADO.

INTERNAL-COMBUSTION ENGINE.

1,260,653.

Specification of Letters Patent. Patented Mar. 26, 1918.

Application filed March 6, 1917. Serial No. 152,853.

To all whom it may concern:

Be it known that I, GEORGE H. DUKE, citizen of the United States, residing at Hotchkiss, in the county of Delta and State 5 of Colorado, have invented new and useful Improvements in Internal-Combustion Engines, of which the following is a specification.

This invention relates to internal-combustion engines and its object is to provide the same with a means whereby the maximum power is developed without an additional fuel supply.

The invention also has for its object to 15 provide the engine cylinder with a variable clearance space for a purpose to be herein-after described.

In order that the invention may be better understood, reference is had to the accompanying drawings forming a part of this specification, and in the drawings,

Figure 1 is a vertical section of the engine, and

Fig. 2 is a similar view with the parts in 25 another position;

Figs. 3 and 4 are enlarged cross-sections on the lines 3—3 and 4—4 of Fig. 1, and

Fig. 5 is a detail showing in elevation a valve actuating rod.

30 Referring specifically to the drawings, 10 denotes the cylinder of the engine in which a piston 11 reciprocates. In the side wall of the cylinder are inlet and exhaust ports 12 and 13, respectively, said ports being positioned diametrically opposite each other.

The inlet port 12 is controlled by a slide valve comprising a plate 14 seating in a recess 15 in the cylinder wall, on the inside of the latter, and so positioned that it covers 40 the port in one position and uncovers it in another position. From the back of the valve plate 14 extends a stem 16 which passes through a slot 17 in the cylinder wall and has connected to its outer end a valve 45 actuating rod 18 operated by a cam 19 on a shaft 20 suitably geared to the engine shaft 21 having a crank 22 to which the connecting rod 23 of the piston 11 is coupled. The end of the valve actuating rod 18 which is 50 connected to the stem 16 is fashioned into a yoke 24 to straddle the intake pipe 25 connecting with the port 12. The lower end of the valve plate 14 has a beveled edge 26 and its side edges are also beveled as shown at 55 27. The walls of the recess 15 against which the beveled edges of the valve plate fit are

beveled to correspond, thereby producing a tight joint to prevent leakage around the valve plate.

The exhaust port 13 is controlled by a 60 slide valve 28 constructed and actuated in the same manner as the valve 14.

In the combustion chamber 29 of the cylinder 10, back of the piston 11, is a movable head 30 forming a closure for said chamber 65 and carrying an ignition device 31 for firing the fuel charge. This head is slidable in the cylinder for a purpose to be presently described.

The combustion chamber 29 also contains 70 a sleeve 32 fitting slidably therein. The head 30 is located inside this sleeve. The length of the sleeve is such that its inner end may strike the back of the piston 11 when the firing stroke takes place, this end 75 of the sleeve being reinforced, as shown at 33, so that it may withstand the impact of the blow against the piston. The outer or upper end of the sleeve is reinforced as shown at 34. In the sleeve are ports 35 and 80 36, which register with the ports 12 and 13, at the proper time.

The outer end of the cylinder 10 has a fixed head 37 provided with a central opening 38 to permit access to the ignition device 85 31. Between the head 37 and the slideable head 30 are located impacting elements 39 for transmitting the movement of the latter to the sleeve 32. These impacting elements are semicircular bars seating at one end on 90 top of the head 30 extending in an upward and outward curve therefrom to bring their other ends in contact with the top reinforced end 34 of the sleeve. The inner surface of the head 37 is shaped to form guides 95 40 for the elements 39. The upper end of the head 30 is of reduced diameter to accommodate the end 34 of the sleeve and to allow the elements 39 to turn freely in a direction to force the sleeve downward as 100 shown in Fig. 2.

The head 30 is prevented from dropping down too far in the cylinder 10 by bolts 41 passing loosely through the head 37 and having springs 42 interposed between their 105 heads and the outside of the head 37, the head 30 being thus yieldingly supported in the combustion chamber 29 of the cylinder.

The engine operates on a four-stroke cycle, the operation being as follows:—

On the suction stroke of the piston 11, the valve 14 is open, and the sleeve 32 is at the

limit of its downward movement, and its port 35 registers with the port 12. At the end of the suction stroke, the valve 14 closes, and at the end of the next, or the compression stroke the piston 11 strikes the sleeve 32 and moves it upward. This movement of the sleeve, through the elements 39 forces the head 30 inward, thereby reducing the clearance space and obtaining a corresponding greater degree of compression. The compressed fuel charge is now fired, whereupon the piston 11 and the head 30 are forced in opposite directions. The head 30 moves upward, and through the elements 39 the sleeve 32 is forced downward, and as the latter was in contact with the back of the piston 11 at the beginning of the firing stroke, the force of the explosion expended against the head 30 is transmitted to the piston, resulting in greater power. On the next stroke, which is the exhaust stroke, the valve 28 opens, and at the end of this stroke the cycle of operations is repeated. The piston also again strikes the sleeve at the end of the exhaust stroke, and the head 30 is forced inward to reduce the clearance space, thereby securing a complete removal of the residual spent gases from the combustion chamber. Fig. 1 shows the position of the parts at the commencement of the firing stroke, and Fig. 2 their position at the end of this stroke.

While the preferred embodiment of the invention has been shown and described, it will be evident that various changes and modifications in the structural details illustrated may be made without a departure from the spirit and scope of the invention as claimed hereinafter. Any other suitable mechanism for transmitting the motion of the head 30 to the sleeve 32 may be provided.

I claim:

1. In an internal-combustion engine, a cylinder, a piston in the cylinder, a slidable head in the cylinder back of the piston, said head being exposed to the explosion pressure and movable thereby outward of the piston, and means engageable with the back of the piston for transmitting said movement of the head to the piston at the begin-

ning of the firing stroke thereof in the same direction the piston moves during said stroke.

2. In an internal-combustion engine, a cylinder, a piston in the cylinder, a slidable head in the cylinder back of the piston, said head being exposed to the explosion pressure and movable thereby outward of the piston, a movable member in contact with the back of the piston at the commencement of the firing stroke thereof, and means for transmitting the aforesaid movement of the head to said member in the same direction the piston moves during the firing stroke. 65

3. In an internal-combustion engine, a cylinder, a piston in the cylinder, a slidable head in the cylinder back of the piston, said head being exposed to the explosion pressure and movable thereby outward of the piston, a sleeve in the cylinder and in contact at one end with the back of the piston at the commencement of the firing stroke, the slidable head being located inside the sleeve, and means for transmitting the aforesaid movement of the head to the sleeve. 75

4. In an internal-combustion engine, a cylinder, a piston in the cylinder, a slidable head yieldingly suspended in the cylinder back of the piston, said head being exposed to the explosion pressure and movable thereby outward of the piston, and means for transmitting said movement of the head to the piston at the beginning of the firing stroke thereof in the same direction the piston moves during said stroke. 85

5. In an internal-combustion engine, a cylinder, a piston in the cylinder, a slidable head in the cylinder back of the piston, said head being exposed to the explosion pressure and movable thereby outward of the piston, a sleeve in the cylinder and in contact at one end with the back of the piston at the commencement of the firing stroke, the slidable head being located inside the sleeve, and means for transmitting the aforesaid movement of the head to the sleeve, the cylinder having side inlet and exhaust ports, and the sleeve having ports adapted to register with said cylinder ports. 95

In testimony whereof I affix my signature,
GEORGE H. DUKE. 100
